UNITED STATES PATENT OFFICE.

HARRY J. GALLAGHER, OF KOKOMO, INDIANA, ASSIGNOR TO KOKOMO BRASS WORKS,
OF KOKOMO, INDIANA, A CORPORATION OF INDIANA.

DESIGN FOR A STAFF-HEAD.

59,074.

Specification for Design. Patented Sept. 20, 1921.

Application filed May 16, 1921. Serial No. 470,007. Term of patent 14 years.

To all whom it may concern:

Be it known that I, HARRY J. GALLAGHER, a citizen of the United States, residing at Kokomo, in the county of Howard and State of Indiana, have invented a new, original, and ornamental Design for a Staff-Head, of which the following is a specification, reference being had to the accompanying drawing, forming part thereof.

Figures 1 and 2 are side elevations of a staff head showing my new design, and

Fig. 3 is an end view thereof.

I claim:

The ornamental design for a staff head as shown.

HARRY J. GALLAGHER.
